UNITED STATES PATENT OFFICE.

RUDOLPH THIEM, OF HAMILTON, OHIO, ASSIGNOR TO GRAF-WEBB IRON MANUFACTURING COMPANY, OF LOUISVILLE, KENTUCKY.

DESIGN FOR A COOKING STOVE OR RANGE.

SPECIFICATION forming part of Design No. 36,301, dated April 28, 1903.

Application filed March 23, 1903. Serial No. 149,211. Term of patent 14 years.

To all whom it may concern:

Be it known that I, RUDOLPH THIEM, a citizen of the United States, residing at Hamilton, in the county of Butler and State of Ohio, have invented a certain new, original, and ornamental Design for Cooking Stoves or Ranges, of which the following is a specification.

My new and ornamental design for cooking stoves or ranges is illustrated in the accompanying drawing, which is a perspective view of a cooking-stove ornamented in accordance with my present invention.

My new design is, as illustrated in the drawing, characterized by surface ornamentation to the stove or range, involving predominant or bold elements A in relief and having scroll

qualities, these elements being intimately associated with floriate elements B in relief, portions of the floriate elements projecting 20 through piercings in the predominant elements A, as at C. This characterizing ornamentation is applied to various door or panel surfaces about the stove or range.

Having described my invention, what I 25 claim as new, and desire to secure by Letters Patent, is—

The ornamental design for a cooking stove or range as herein shown and described.

RUDOLPH THIEM.
